(57) **CLAIM**

The ornamental design for a miniature engraving machine as shown and described.

DESCRIPTION

FIG. 1 is a front, top perspective view of a miniature engraving machine showing my new design.

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear, bottom perspective view thereof.

The broken lines in the drawings depict portions of the miniature engraving machine that form no part of the claimed design.
